SLIDE LOADER ACCESSORY FOR A SLIDE PROJECTOR

Robert M. Simonelli, Palatine, Ill., assignor to GAF Corporation, New York, N.Y., a corporation of Delaware

Filed Apr. 14, 1969, Ser. No. 16,736

Term of patent 14 years

Int. Cl. D16—07

U.S. Cl. D61—1

FIG. 2.

FIG. 3.

FIG. 4.

FIG. 1.

FIG. 1

FIG. 2

FIG. 1 is a perspective view of a slide loader accessory for a slide projector embodying my new design;

FIG. 2 is a rear elevational view thereof;

FIG. 3 is a front elevational view thereof;

FIG. 4 is a left-side elevational view thereof, the other side being a mirror image of the side shown;

FIG. 5 is a top plan view thereof; and

FIG. 6 is a bottom plan view thereof.

I claim:

The ornamental design for a slide loader accessory for a slide projector, substantially as shown and described.
